HINGE COVER

Everett B. Arnold, Jr., Detroit, Mich., assignor to General Motors Corporation, Detroit, Mich., a corporation of Delaware

Application November 14, 1956, Serial No. 622,218

5 Claims. (Cl. 16—148)

This invention relates generally to hinge devices and particularly to hinge devices of the type used to swingably hang automotive vehicle doors.

Because of the emphasis which is increasingly being placed on the appearance of automotive vehicles, more and more effort is being exerted toward covering or making as inconspicuous as possible various of the functioning assemblies which although necessary (for proper utilization of the vehicle) are deemed to present an unpleasing effect appearancewise. Automotive vehicle door hinge assemblies, which are a prime example of the type of assemblies referred to above and which form the subject of this invention, at one time had portions thereof located in full view when the doors were in the open or closed position. Changes in body design and styling however finally led to the formation of hinge assemblies which were hidden, i.e., not visible when the doors were in the closed position. In recent years, with the increases in the thicknesses of the door and body panels and the complications involved in swinging the doors relatively to their supporting body sections so that they are free of obstructions, it has been necessary to utilize movable center hinge assemblies whose hinge butts are relatively large and require large openings in the body sections in order to have their required degrees of movement. These hinge assemblies have grown in complexity and now contain a multiplicity of links, springs, and other parts which, if viewable, are considered to present an unpleasing appearance whether the door is in the open or partially opened position. The complexity of such hinge assemblies and the room required for the various elements thereof add to the difficulty of providing a suitable hinge assembly covering which will not interfere with the movements of the hinge assembly and still provide a cover for such assembly when the assembly is in the door open position.

Accordingly, it is an object of this invention to provide for hinge opening covers which appear particularly adaptable for use in conjunction with the hinges found in the modern automotive vehicle.

It is a further object of this invention to make such covers in more than one piece so that they may more compactly combine with such hinges and unfold or move as the door is opened to perform their covering function and, likewise, fold when the door is closed, so that they do not interfere with the other working parts of the hinge assemblies.

For the above and other objects of this invention reference may be had to the accompanying detailed description and drawings in which:

Fig. 1 is a side elevation of an automotive vehicle illustrating an application of the hinge assembly between a right rear door and a right rear quarter panel of a vehicle body in which such covers are advantageously utilized.

Fig. 2 is a fragmentary view taken substantially on the line 2—2 of Fig. 7 with parts shown in section and serves to illustrate one of the links connecting one of the hinge

2

butts to the hinge box and with the hinge butt in the door full open position.

Fig. 3 is a view similar to Fig. 2 and is taken substantially on the line 3—3 of Fig. 9 but is of the lower hinge device with the hinge butt shown in the door full open position.

Fig. 4 is a detailed view taken on the line 4—4 of Fig. 10 and illustrates the stabilizing link extending between lower and upper hinge devices and its connection to one of the links which pivotally connects the hinge butt to the hinge box.

Fig. 5 is a detailed view with parts broken away and in section illustrating the adjustable means for limiting closure of the door.

Fig. 6 is a view greatly enlarged taken substantially on the line 6—6 of Fig. 1 showing a hinge assembly with the hinge parts in the door fully closed position and the novel hinge cover combined therewith folded back out of the way so that it does not interfere with the rest of the hinge parts.

Fig. 7 is a view similar to Fig. 6 except that the hinge parts including the novel hinge cover are shown in the door full open position wherein the hinge cover closes the opening in the hinge cover plate so as to conceal the working parts of the assembly located in the hinge box.

Fig. 8 is a view taken substantially on the line 8—8 of Fig. 1 but greatly enlarged illustrating a second hinge assembly which utilizes a somewhat different type or form of hinge cover plate wherein the hinge parts and the novel hinge cover assembly are also shown in the door full closed position.

Fig. 9 is a view similar to Fig. 8 except that the parts of the modified hinge assembly and novel articulated hinge cover are shown in the door full open position.

Fig. 10 is a view in elevation with parts broken away and in section taken substantially on the line 10—10 of Fig. 6 illustrating the details of the connections between the upper and the lower hinge assemblies and their combination with the novel hinge covers.

Referring first to Fig. 1 of the drawings, an automotive vehicle 2 is shown which includes a rear right body quarter panel 4 and a right front door 6 and a rear door 8. The rear door 8 as indicated by means of the dotted lines shown thereon is hinged supported on the rear quarter panel 4 by the new hinge assembly identified generally by a numeral 10. The hinge assembly 10 includes an upper hinge device 12 and a lower hinge device 14.

The details of the lower hinge device 4 are best illustrated in Figs. 3, 8, 9 and 10. Upon reference to those figures, it will be observed that hinge device 14 includes a gooseneck hinge butt 16 which is suitably rigidly fastened at one end thereof to the rear door 8 by the nut and bolt assemblies 18 so as to swing therewith. The opposite end 20 of hinge butt 16 is pivotally connected (as best seen in Fig. 3) by a pin 22 to one end 24 of a bifurcated link 26 which is pivotally connected to the usual hinge box 27 by means of pivot pins 23. Also pivotally connected to the hinge box 27 at one end by means of a pin 30 is one end 32 of a control hinge link 34 whose opposite end 36 is pivotally connected at the point 38 to the gooseneck hinge butt 16.

As best seen in Figs. 8, 9, and 10, a pair of pivoted hinge covers 40 and 42, U-shaped or channel-like in cross section, are pivotally connected together and between the hinge box 27 and the gooseneck hinge butt 16 at the points 44 and 46, respectively. The entire lower hinge device so far described is mounted in the recess normally provided in the rear quarter panel 4 and fixed rigidly in place by means of the threaded bolt and nut assemblies 48. When the hinge assembly 14 is properly fixed in place in

rear quarter panel 4, a hinge cover plate 43 is fixed to the transversely extending vertical panel or bulkhead 45, plate 43 being provided with an aperture 47 through which the hinge butt 16 extends. As previously mentioned, the covers 40 and 42 are U-shaped or channel-like in section so that they can pivotally fold or nest together without interfering with the pivot movement thereof. As indicated in Fig. 8, when the hinge assembly is in the door closed position, the covers 40 and 42 take a substantially right angle position relative to each other in a location which keeps them from interfering with the other elements of the hinge assembly 14.

Observing now Fig. 9, it will be seen that when the hinge butt 16 is moved to the full door open position, the covers 40 and 42 straighten out into substantial alignment with each other to take the position shown, thereby covering the opening in the cover plate 43 so that observers cannot see or peer in and view the unsightly elements and other mechanical portions of the hinge assembly 14 located in hinge box 27. Although not so utilized in the present instance, the cover plates 40 and 42 could be made to limit the opening movement of the hinge butt 16, thus acting as a limiting device for hinge butt 16 as well as improving the appearance of the panel 45 in the proximity of the hinge assembly 14.

Referring to Figs. 2, 6, and 7, the upper hinge device 12 includes a hinge box 50 having pivotally connected thereto by means of pins 52 a bifurcated link 54. The bifurcated end of link 54 has pivotally connected between the bifurcations 56 and 58 thereof one end 60 of a gooseneck hinge butt 62. The opposite end of link 54 is pivotally connected to hinge box 50 by pins 55. The opposite end of hinge butt 62 is connected to the upper portion of the rear door 8 by bolt and nut assemblies 64. The upper hinge assembly 12 is mounted in the recess provided in the rear quarter panel 4 and is rigidly held in place by the bolt assemblies 66 and 68 which fasten the hinge box to a bulkhead 70. It will be observed that the structure so far described for the upper hinge device will not in and of itself serve to stabilize the movement of the hinge butt 62 either about a fixed center or a movable center moving along a predetermined path. However, as best noted in Figs. 1, 4, and 10, the upper and lower hinge devices 12 and 14 are connected together in a manner hereinafter set forth. Upon reference to Fig. 4 it will be seen that the link 54 of the upper hinge device 12 is provided with an arm 72 and that the link 26 of the lower hinge device 14 is provided with a similar arm 74. The arms 72 and 74 have extending substantially vertically therebetween and rigidly fixed thereto by means of studs 76 and 78 a stabilizing member or bar 80. The bar 80 serves as a link between the upper link 54 of the upper hinge device 12 and the lower link 26 of the lower hinge device 14 so as to impart in conjunction with the door 8 the same swinging movement of the hinge butt 16 to the hinge butt 62.

It will be appreciated that the movements of the upper and lower hinge devices 12 and 14 are interrelated and that the upper hinge device is not provided with a control link similar to the control link 34 of the lower hinge device. The binding, which might be present if both door hinge assemblies were to include control links such as is shown in the lower hinge device of the present application, is thus effectively prevented. Furthermore, more room is made available in the upper hinge assembly for the presence of the door hold open and the spring door assist.

Turning again for a moment to Figs. 6 and 7 it will be seen that the upper hinge device 12 has pivotally connected to the hinge box 50 at the point 82 an arm or lever 84 which serves as a door hold open. The arm 84 as viewed in Figs. 6 and 7 is normally biased in a counterclockwise direction by means of a helical coil spring secured at one end thereof and to the hinge box 50 at the point 86. Movement of the hold open 84 is limited by

a hold open stop comprising a pin 88 fixed to the hinge box 50. It will be noted that the hinge butt 62 is provided with a pin or follower 90 which, as the butt 62 swings from the closed position shown in Fig. 6 to the open position in Fig. 7, moves through an intermediate hold open position defined by a recess 92 or shoulder to a full hold open recess 94 where the pin 90 abuts a shoulder 96.

To regulate proper closure of the door 8 an adjustable door closing limit stop has been provided. This is best seen in Figs. 5, 6, and 7 and comprises an adjustable screw 98 supported by a bracket 100 fixed to the hinge box 50. The gooseneck 62 is provided with a shoulder 102 which engages the end of screw 98 upon predetermined closing of door 8 and gooseneck 62. If the door 8 tends to swing too far closed a simple adjustment of screw 98 will correct such overclosure.

To assist in the opening of the door a torque link 104 is provided which has one end fixed to the hinge box 50 by a bracket and studs 106. (See Figs. 6, 7, and 10.) The torque rod is bent in the form of a crank and has the opposite end fixed by a bracket and studs 108 to the gooseneck 62. The rod 104 is formed so that it is relatively unstressed when the door is in the full open position and is increasingly stressed as the door closes.

After the upper hinge assembly 12 has been mounted in place in the rear quarter panel 4, an upper hinge cover plate 110 is fixed to the transverse forward face of the quarter panel 4 in much the same manner of the cover plate 43. The cover plate 110 is also provided with an opening 111 through which the gooseneck hinge butt 62 extends. To cover the opening 111 in the cover plate 110 a slightly different split hinge cover assembly is provided which comprises a first cover piece 112 which appears shoe-like in shape and is rigidly fixed to the gooseneck hinge butt 62 at the primary bend 120 of the gooseneck so that a sliding surface 122 of the piece 112 is substantially faired into the surface 124 of the gooseneck facing outwardly when the gooseneck is in the full door open position. A second cover piece 114 is pivotally mounted in the hinge box at the point 116. Piece 114 is U-shaped or channel-like in character so that the sides thereof tend to embrace the piece 112. Piece 114 is made of some suitable sheet metal material. Formed on the free end 126 of the piece 114 is a smoothly faired tab 128 which is adapted to ride on the smoothly faired surfaces 130, 132, and 122 of the piece 112. To maintain piece 114 in constant frictional engagement with piece 112, a torsion spring 118 has been provided which has an end anchored to the hinge box 50 and the opposite end abutting piece 114 tending to constantly bias it in a counterclockwise direction against piece 112. It will thus be seen that the piece 112 moves with the hinge butt 62 so that when the hinge butt moves to the door full open position as shown in Fig. 7, the piece 112 serves to cover a part of the opening 111. The remaining portion of the opening is then covered by the hinge cover piece 114 which takes the position shown by the tab 128 riding on the surfaces 122, 132, and 130, respectively, and in that order. Again, as seen in Fig. 6, the hinge covers fold into a very compact assembly located so that they do not interfere with the operation of the other elements of the hinge assembly.

From the foregoing description it may now be appreciated that two types of hinge cover plates or articulated type have been shown and described which may be combined with hinge assemblies so as to cover the openings through which the hinge butts normally extend to render more pleasing the appearance of the body in addition to preventing foreign pieces and other matter from finding their way into such openings.

I claim:

1. In an enclosure including a door and a wall having a hinge assembly recess therein, a cover member over said recess and having a rectangular opening therein,

a hinge assembly mounted in said recess and including a hinge butt pivoted to said wall in said recess and extending through said opening to said door and rigidly fastened thereto, said hinge butt being mounted in said opening to move through the space of said opening from one edge to an opposite edge thereof when said door is moved from its full closed position to its full open position and means to cover said opening when said hinge butt is in the door full open position comprising a foldable cover, one of its ends being pivotally mounted on said hinge butt within said recess adjacent the aforementioned opposite edge of said opening when said hinge butt is in its door full open position and its opposite end being pivotally connected to said wall within said recess adjacent the one edge of said opening, the attachment of said ends to said hinge butt and wall locating said cover in a folded condition in said recess when said butt is in the door closed position and in an unfolded condition across said opening when said butt is in the door full open position, said cover being of sufficient area in its unfolded condition to substantially cover the area of said opening.

2. In an automobile body including a door and a body panel having a hinge assembly recess, a cover member over said recess and having an elongated opening therein, a hinge assembly mounted in said recess and including a hinge butt pivoted to said body in said recess and extending through said opening to said door and rigidly fastened thereto, said hinge butt being mounted in said opening to move through the space of said opening from one edge to an opposite edge thereof when said door is moved from its full closed position to its full open position and an elongated multiple piece cover to cover said opening when said hinge butt is in the door full open position comprising a first cover piece mounted on said hinge butt within said recess, having an end adjacent the aforementioned opposite edge of said opening when said hinge butt is in its door full open position, a second cover piece having an end pivotally connected to said panel adjacent the one edge of said opening within said recess, and means maintaining said pieces in engagement with each other for relative movement with respect to each other, said points of attachment of said cover pieces to said panel and said hinge butt and said means thereby locating said pieces in a folded condition in said recess, when said butt is in the door closed position and in an extended condition across said opening when said butt is in the door full open position, said cover being of sufficient area in its unfolded condition to substantially cover the area of said opening.

3. In an automobile body including a door and a body panel having a hinge assembly recess, a cover member over said recess and having an elongated opening therein, a hinge assembly mounted in said recess and including a hinge butt pivoted to said body in said recess and extending through said opening to said door and rigidly fastened thereto, an elongated multiple piece cover to cover said opening when said hinge butt is in the door full open position comprising a first cover piece rigidly mounted on said hinge butt within said recess to swing therewith, a second cover piece pivotally connected to said panel within said recess, biasing means associated

with said second cover piece and said panel biasing said second cover piece into constant engagement with said first cover piece, said points of attachment of said cover pieces to said panel and said hinge butt and said biasing means locating said pieces in a folded condition when said butt is in the door closed position and in an extended condition across said opening when said butt is in the door full open position.

4. In an automobile body including a door and a body panel having a hinge assembly recess, a cover member over said recess and having an elongated opening therein, a hinge assembly mounted in said recess and including a hinge butt pivoted to said body in said recess and extending through said opening to said door and rigidly fastened thereto, said hinge butt being mounted in said opening to move through the space of said opening from one edge to an opposite edge thereof when said door is moved from its full closed position to its full open position and means to cover said opening when said hinge butt is in the door full open position comprising a pair of pivotally attached foldable cover pieces one of which has an end pivotally fastened to said hinge butt within said recess adjacent the aforementioned opposite edge of said opening when said hinge butt is in its door full open position and the other of which has an end pivotally attached to said panel within said recess adjacent the one edge of said opening so that said pieces are folded in said recess when said butt is in the door closed position and unfolded across said opening when said butt is in the door open position, said cover being of sufficient area in its unfolded condition to substantially cover the area of said opening.

5. In an enclosure including a door and a wall having a hinge assembly recessed therein, a hinge assembly mounted in said recess and including a hinge butt pivoted to said wall in said recess and extending out of said recess to said door and rigidly fastened thereto, said hinge butt being mounted in said opening to move through the space of said opening from one edge to an opposite edge thereof when said door is moved from its full closed position to its full open position and means to cover said recess when said hinge butt is in the door full open position comprising a foldable cover, said cover having a first end portion pivotally mounted on said hinge butt within said recess adjacent the aforementioned opposite edge of said opening when said hinge butt is in its door full open position and having an opposite end portion pivotally connected to said wall within said recess adjacent the one edge of said opening, the attachment of said ends to said door and wall being located with respect to remaining portions of said cover to retain said cover in a folded condition in said recess when said butt is in the door closed position and in an unfolded condition over said recess when said butt is in the door full open position, said cover being of sufficient area in its unfolded condition to substantially cover the area of said opening.
